(57) **CLAIM**

I claim the ornamental design for a tub, as shown and described.

DESCRIPTION

FIG. 1 is a front, top perspective view of a tub for bathing showing my new design;

FIG. 2 is a top plan view thereof;

FIG. 3 is a front elevation view thereof;

FIG. 4 is a right side elevation view thereof;

FIG. 5 is a left side elevation view thereof; and,

FIG. 6 is a rear elevation view thereof.
